UNITED STATES PATENT OFFICE.

WAINO ILMA AND MATT SAARI, OF WEIRTON, WEST VIRGINIA.

COMBINED MATCH-BOX CASE AND ASH RECEIVER.

Application filed April 18, 1925. Serial No. 24,020.

To all whom it may concern:

Be it known that we, WAINO ILMA, a citizen of Finland, and MATT SAARI, a citizen of the United States of America, and residents of Weirton, county of Hancock, and State of West Virginia, have invented certain new and useful Improvements in Combined Match-Box Cases and Ash Receivers, of which the following is a specification.

10 This invention relates broadly to smokers' articles, and it has for its primary object to provide a pocket match-box case having combined therewith an emergency receptacle for ashes from a cigar or cigarette, 15 or for discarded short stubs of cigars or cigarettes.

A further object is to provide a simple and inexpensive two-compartment box or case of the character mentioned.

20 In describing the invention in detail, reference is herein had to the accompanying drawings, in which—

Figure 1 is a top plan view of the invention;

25 Figure 2 is a section of the same on line 2—2, Fig. 1;

Figure 3 is a rear edge view;

Figure 4 is a front edge view, partly in broken section; and

30 Figure 5 is an enlarged detail section on line 5—5, Fig. 4.

Referring to said drawings, 1 indicates the top, 2 the bottom, and 3 and 4 the opposite side walls of a substantially rectangular case adapted for the snug reception of a pocket match-box of an ordinary commercial size, said case being open at its opposite ends for the introduction and removal of such match box and having the side-wall 3 thereof provided with an oblong opening 5 for exposing the usual striking surface of an enclosed match box. Said top 1, the bottom 2 and the side wall 3 are formed by shaping a single sheet metal blank, while the wall 4, as will hereinafter be explained, is made of a separate attached piece of sheet material.

40 A compartment 6 located laterally with respect to the match-box case described is formed, in part, by continuing, or prolonging, the flat bottom 2 of the case beneath and outward from the side wall 4 throughout a suitable distance, forming a bottom 2^a located in the same plane as said bottom 2. Formed integral with and extending upward from the extended bottom 2^a is a wall 7 which

constitutes the opposite end walls as well as a side wall of said compartment 6, having its end portions curved back to meet said side wall 4, as shown. The said curved portions of said wall 7 have short terminals 8 which are turned inwardly to overlie the bottom 2^a. Each of said inturned terminals 8 is provided with one or more slit-like apertures 9 in which are received tongues 10 formed on the side wall 4 and by which the latter is secured in place, the ends of said tongue being turned back into seated relation to said terminals, as shown.

Having hinge connection with the forward end of the top 1, as shown at 11, is 70 a cover 12 for the compartment 6, said cover having an edge contour corresponding to the wall 7 and having a resilient tongue-clasp 13 adapted to engage with the wall 7 for retaining the cover in its closed position.

The compartment 6 is designed to serve as an emergency receiver for burnt matches, cigar or cigarette ashes, partially consumed cigars or cigarettes, and the like.

80 The bottom 2 of the case is provided with an arcuately curved, or crescent-shaped, slit or opening 14 whereby is formed a tongue 15 which may be pressed inward into yielding binding engagement with the bottom 85 of a match box for retaining the latter against chance outward movement.

It will be noted that the combination case and receptacle herein described has a form and is capable of being made in a size adapted to be readily accommodated in the pockets of users.

What is claimed is—

1. A holder comprising a case for match boxes and a container for ashes and the like 95 parallel to said case, said holder consisting of a bottom common to said case and said container, a top wall and a side wall for said case formed integral with said bottom, said top wall being of less length than said bottom wall, an integral upright compartment wall formed at the outer edge of said bottom wall, said compartment wall being curved back at its ends to form end walls for the compartment, said end walls having inwardly directed terminals overlying said bottom, and a wall disposed in transverse overlying relation to said bottom and having its ends attached to said terminals, and a cover for said compartment hinged 105 to the front edge of the top wall,

2. A holder divided intermediate its ends into two compartments, one of said compartments constituting an open-ended case for match boxes and the other a container for ashes and the like, said holder comprising parallel top and bottom walls and a side wall, said bottom having greater length than said top, an upright compartment wall formed at the front edge of said bottom and having its ends turned back to

form end walls for said container, a transverse division wall disposed parallel to the said side wall of the case and attached to the end walls of the container, and a cover for said container hinged to the front edge 15 of the top wall.

In testimony whereof we affix our signatures.

WAINO ILMA.
MATT SAARI.
